ARTICLE RACK DEVICE

John S. Connors, Cleveland, Ohio

Application August 1, 1946, Serial No. 687,674

1 Claim. (Cl. 211—100)

1

This invention relates to rack devices for supporting articles, such as towels, stockings, and the like, and more particularly to a device of this type which has a plurality of extensible rods for supporting articles and which may be folded to be housed within a closed box when not in use.

Article racks are commonly used in homes which comprise a plurality of rods extending from a wall support for receiving kitchen or bath towels, stockings and the like. I am aware that certain such racks have the rods hinged at the support whereby the rods may be rotated against the wall when not in use. However, these racks are unsightly and detract from the appearance of a modern kitchen or bathroom.

Further, the rods are exposed to the usual dust floating in a kitchen or bathroom and unless a user remembers to wipe the rods before use, towels, stockings and the like may become streaked with dust or dirt.

I have devised an article rack of this general type which is housed in a relatively small box wherein the back of the box becomes the support for the rods when secured to a wall and a close fitting cover minimizes accumulation of dust on the rods when not in use. Further, the box may be attractively designed to blend with the appearance of the room where installed and does not give the appearance of a towel rack or the like when not in use. In use the cover is raised and is inclined at a slight angle to be self-supporting in the open position. The rods are mounted on a curved bar and are adapted to extend horizontally in radial directions. Also, the rods are folded when housed and may extend several times their folded length when in use.

It is a primary object of the invention to provide an improved towel or the like rack.

Another object of the invention is to provide a towel or the like rack which is adapted to be enclosed in a box secured to a wall when not in use.

Another object of the invention is to provide a rack of the above type comprising a plurality of rods which are extensible for use.

Another object of the invention is to provide a rack of the above type which is economical of manufacture and assembly.

A further understanding of the objects and the invention will be evident from a consideration of the following description and drawings wherein:

Fig. 1 is a perspective view of an article rack embodying my invention.

2

Fig. 2 is a perspective view of the rack of Fig. 1 with the cover closed.

Fig. 3 is a fragmentary transverse section taken along line 3—3 of Fig. 2.

Fig. 4 is a fragmentary vertical section taken along line 4—4 of Fig. 3.

Fig. 5 is an enlarged sectional view showing the hinge arrangement.

Fig. 6 is a fragmentary view showing the support end of a rod, and

Fig. 7 is a fragmentary view showing a hinge arrangement from connecting the rod sections.

Referring now to the drawings, and particularly Fig. 1, I have indicated at 10 the back or support member for the rack which is generally rectangular in form and may be a flat plate as shown or may have a peripheral flange maintaining the plate proper slightly spaced from a wall to which it is attached. The member 10 may be formed of metal, plastic, wood or other suitable material and secured to a wall or the like in any convenient manner as by screws 11. Supported by member 10 are a plurality of rods generally indicated at 12. Each rod has a plurality of hinge connected sections, the inner sections indicated at 13 having one end slotted as shown in Fig. 6 to provide a rectangular opening 14 terminating in a parti-circular opening 15. A curved bar 17 is projected through the slotted end of sections 13 and through spacing collars 18.

Bar 17 may be secured to member 10 in any suitable manner as by welding a generally U-shaped bracket 19 to member 10 with the arms 35 of the bracket being sufficiently flexible to snap over the ends of bar 17 as indicated in Fig. 3. I preferably provide spacing collars 21 between the arms of bracket 19 and the end rods 13. Also, I contemplate that bracket 19 may be omitted and the ends of bar 17 may be directly welded or otherwise secured to support 10.

It will be noted by reference to Fig. 4 that bar 17 is generally rectangular in cross section with the vertical faces curved to slightly conform to 45 the inner diameter of collars 18 and the diameter of openings 16 in rod sections 13. Normally the rods 12 will hang vertically as indicated in Fig. 1 and when it is desired to extend the rods horizontally for use, the rods are rotated through 50 90° to a horizontal position and forced inwardly towards support member 10 whereby the opening 14 of section 13 will engage bar 17 to maintain the sections in a horizontal position. Each rod may comprise several sections although I 55 have found three to be a suitable number. Fig.

7 shows an arrangement for hingedly connecting the sections and it will be noted that the lower or outer end of section 13 is reduced along a quarter-circle as at 22 and the extended half-width 23 is bent at right angles to form a finger 24.

The upper end of the connected section 26 is formed to provide a three-quarter circle as indicated at 27 and a notch 28. When section 13 is moved to a horizontal position it will be rotated counter-clockwise (Fig. 7) and the finger 24 will enter slot 28 thereby supporting section 26 in a horizontal position. The sections are pin connected as at 29 and for storage section 13 are dropped to a vertical position by an outward pull and sections 26 will be rotated counter-clockwise about pins 29 to assume positions as illustrated in Fig. 1. Additional sections may be connected to sections 26 by the hinge construction illustrated in Fig. 7.

The cover indicated at 31 is preferably formed by bending a flat sheet to form upstanding sides 32 and an upstanding end 33 with a slight gap between the end and sides as indicated at 34. The opposite end 36 forms a tight contact with the sides. The cover support comprises a pair of L-shaped brackets 37 welded or otherwise suitably secured to back member 10. The outstanding legs of the brackets are formed as indicated in Fig. 5 to provide a notch 38 and an arm 39 with a rounded upper end to which the sides 32 of the cover are pin connected as at 41. The notches 38 provide clearance for the back of the cover when in the position of Fig. 1 and pins 41 are disposed so that the cover is inclined against the wall in the open position to be self-maintaining.

The rack described is economical of manufacture and assembly, provides a substantially dustproof closure when not in use which is attractive in appearance, and provides a simple arrangement for extending and folding the rods.

Although I have shown and described a preferred form of the invention I contemplate that numerous and extensive departures may be

made therefrom without departing from the spirit of the invention and the scope of the appended claim.

What I claim is as follows:

- 5 A foldable article rack comprising a support, a curved bar of generally rectangular cross section fixed to the support, a plurality of multi-section article supporting rods supported by the bar, the inner section of each rod having a slot therein through which the bar projects with the slot having an enlarged portion whereby the inner section may be rotated freely about the bar and a reduced portion lockable with the bar when the inner section is rotated to horizontal position and moved horizontally, spacing collars on the bar engaging adjacent inner sections whereby the inner sections will be restrained to extend in substantially radial directions when moved to horizontal position, each rod having an outer section hinged to the inner section whereby the outer section may be rotated in one direction to be substantially co-extensive with the inner section, and interlocking means between the inner and outer sections whereby when the outer section is rotated in the opposite direction it may be supported in horizontal position by the inner section.
